CLAIM(51) LOC (12) Cl. **03-01**

The ornamental design for a hose bag, as shown and described.

(52) U.S. Cl.

USPC ..... **D3/246****DESCRIPTION**(58) **Field of Classification Search**

FIG. 1 is a front, top, right-side perspective view of the hose bag of the present invention;

USPC D3/232-233, 240-243, 245-246

FIG. 2 is a front view of the hose bag design shown in FIG. 1;

CPC A45C 1/024; A45C 3/06; A45C 3/08

FIG. 3 is a back view of the hose bag design shown in FIGS. 1 and 2;

See application file for complete search history.

FIG. 4 is a top view of the hose bag design shown in FIGS. 1-3; and,

(56) **References Cited**

FIG. 5 is a back, bottom, left-side view of the hose bag design shown in FIGS. 1-4, with a back, bottom, right-side perspective view being a mirror-image of FIG. 5.

U.S. PATENT DOCUMENTS

The drawings show a hose bag.

D404,913 S * 2/1999 Campbell D3/245

The zipper, zipper pull tab, zipper slider body, and zipper flaps are shown in broken lines and form no part of the claimed design. Broken lines shown elsewhere in the drawings depict lines of stitching and do form part of the claimed design. All broken lines shown in FIG. 5 depict lines of stitching and do form part of the claimed design.
